The ornamental design for a pad for a seabed mat, as shown and described.

DESCRIPTION

FIG. 1 is a side view of an embodiment of a pad for a seabed mat;

FIG. 2 is a top view of the pad of FIG. 1;

FIG. 3 is a side view of an embodiment of a pad for a seabed mat;

FIG. 4 is a top view of the pad of FIG. 3;

FIG. 5 is a side view of an embodiment of a pad for a seabed mat;

FIG. 6 is a bottom view of the pad of FIG. 5; and,

FIG. 7 is a perspective view of the pad of FIG. 5.

The broken lines shown in the drawings illustrate portions of the pad for seabed mat that form no part of the claimed design.
